DESIGN FOR AN ACOUSTICAL TILE

Louis Romanelli, Chicago, Ill., assignor to Certain-Teed Products Corporation, Ardmore, Pa., a corporation of Maryland

Application December 4, 1948, Serial No. 149,981

Term of patent 7 years

(Cl. D68—1)

To all whom it may concern:

Be it known that I, Louis Romanelli, a citizen of the United States residing at Chicago, in the county of Cook and State of Illinois, have invented a new, original, and ornamental Design for Acoustical Tiles, of which the following is a specification, reference being had to the accompanying drawing, forming part thereof.

In the drawing,

Fig. 1 is a front face view of an acoustical tile showing my new design; and

Fig. 2 is an edge view of said tile.

I claim:

The ornamental design for an acoustical tile, as shown.

LOUIS ROMANELLI.
